UNITED STATES PATENT OFFICE.

HARRY ARTHUR FOOTNER, OF HARRISBURG, PENNSYLVANIA, ASSIGNEE TO
ELLIOTT-FISHER COMPANY, A CORPORATION OF DELAWARE.

CROSS-FOOTER REGISTER FOR WRITING ADDING MACHINES.

Application filed December 31, 1920. Serial No. 384,096.

To all whom it may concern:

Be it known that HARRY A. FOOTNER, a citizen of the United States, residing at Harrisburg, in the county of Dauphin and State of Pennsylvania, has invented certain new and useful Improvements in Cross-Footer Registers for Writing Adding Machines, of which the following is a specification, reference being had therein to the accompanying drawing.

This invention relates to a register for writing-addition machines.

The object of the invention is to produce a register or adding mechanism adapted more particularly for operation by an actuating mechanism of the ten key selective denomination type and which, while responsive to the requirements of both addition and subtraction, will be positive and accurate in operation, simple and durable in construction and guarded by safety provisions against breakage or derangement resulting from unintelligent operation or missetting.

To the accomplishment of this general object and various subordinate objects, which will appear as the succeeding description is developed, a preferred embodiment of the invention is illustrated in the accompanying drawings and defined in the appended claims.

In said drawings:—

Fig. 1 is a vertical section through the register, organized for addition and with the parts positioned as at the beginning of the adding operation.

Fig. 2 is a plan view of the subject matter of Fig. 1.

Fig. 3 is a rear elevation of the register.

Fig. 4 is a horizontal section on the line A—A of Fig. 1.

Fig. 5 is a bottom plan view with the casting in section.

Fig. 6 is a rear view of the control bar showing the adding and subtracting cams.

Fig. 7 is a detailed perspective view of the master wheel carriage.

Fig. 8 is an elevation of a portion of the register showing the master wheel locks.

Fig. 9 is a detailed perspective view of the gear shifter. Figs. 9^a and 9^b are detail views.

Fig. 10 is a similar view of the upper bearing of the master wheel advancing mechanism.

Fig. 11 is a detailed perspective view of the lower bearing.

Fig. 12 is a detailed perspective view of one of the number wheels.

Fig. 13 is a sectional view showing the restoring mechanism in normal position.

Fig. 14 is a similar view showing in dotted lines the position assumed by the parts of the restoring mechanism during the depression of the restoring lever and showing in full lines the positions assumed by the parts when the restoring lever has been moved down sufficiently to cause the full stroke pawl to be withdrawn from the rack.

Fig. 15 is still another view of this character with the restoring lever fully depressed and the full stroke pawl caught and held in its inoperative position by its detent.

Fig. 16 is another view of this subject matter showing the restoring lever returning and the full stroke pawl about to be released from its detent.

By way of premise it may be stated that my invention is more particularly concerned with the equipment of what is known to commerce as the Elliott-Fisher bookkeeping machine, in which the printing mechanism moves longitudinally of a stationary platen for line spacing and transversely of the platen for letter spacing. The printing mechanism, which is of the type bar and key or typewriter class, is mounted on a movable carriage which serves not only to advance the printing mechanism to progressive denominational positions of a column, 20 printed on the stationary work sheet, but also serves to advance a master actuator or wheel to successive denominational positions of a relatively fixed adding device or register, one or a number of which may be employed, accordingly, as one or a number of columns are to be printed and added. The master wheel is operated from the keys and moves a number of increments, corresponding to the value of the particular key depressed.

The master wheel in turn effects a corresponding rotation of a number wheel of the register, which corresponds in denominational position to that of the digit printed. Obviously, therefore, as numbers are printed in columns the values of the printed numbers will be accumulated in the register or registers and the total will be disclosed at the sight opening or openings of the latter.

It is also proposed in this type of machine to provide what is known as a grand totalizer or cross-footer. This is an additional adding device or register which is operated 5 in synchronism with the registers first mentioned so as to effect a computation embracing the computations effected by a plurality of the other registers.

My invention relates to the construction 10 of a register which, while not limited to such application, is more particularly designed and adapted for use as the grand totalizer or cross-footer of an Elliott-Fisher machine. While it is not deemed to be necessary to 15 illustrate the entire machine for the purpose of this disclosure, it is thought that the foregoing brief statement of the relation in which the invention is employed will serve to facilitate a clearer understanding of the 20 register mechanism.

Referring now to the drawings, 1 indicates the carriage of the Elliott-Fisher machine of commerce, upon which is supported, as stated, a master wheel 2, rotated by means 25 of adding keys and serving to rotate the number wheels 3 of one or more relatively fixed adding devices or registers 4. It may be stated in passing that these registers are mounted on what is known as the line space 30 frame, upon which the carriage 1 travels under the control of the usual escapement mechanism. The master wheel 2 is fixed to a shaft 5 extended to the end of the carriage where it is equipped within the cross-footer 35 casing 6 with a gear 7 meshing with a reversing pinion 8 in constant mesh with the gear 7 but shiftable laterally to two positions, in one of which, to-wit: that indicated in Fig. 2, it meshes with a pinion 9 fixed to the master wheel shaft 10 and in the other of which, it is disengaged from the pinion 9 but engaged with one side of a twin pinion 11, the other side or member of which is in constant gear with the pinion 9 on the 45 shaft 10. Thus it will be seen that when the master wheel 2 is rotated to add, the gear 7 will rotate the shaft 10 through the pinions 8 and 9, the rotation of the two master wheel shafts 5 and 10 being in the 50 same or adding direction. If, however, the pinion 8 is shifted out of mesh with the pinion 9 and into mesh with one side of the twin pinion 11, the interposition of the twin gear between the pinions 8 and 9 will cause 55 the direction of motion transmitted to the master wheel shaft 10 to be reversed for subtraction. The necessary shifting of the reversing pinion 8, to secure addition or subtraction in the register, is effected automatically. Mounted to slide on two transverse bars 12 and 13 is a gear shifter 14. (See Figs. 1, 3 and 9.) This shifter engages the grooved hub of the pinion 8 and is provided with a stud 15 engaged by the bifurcated 60 end of one arm 16 of a bell crank 17 ful- crumed at 18 on a rigid block 19 and having a horizontally disposed arm 20, at the extremity of which is a roller 21 adapted to ride upon a subtracting cam 22, adjustable upon a control bar 23. Normally the gear shifter 14 occupies the position shown in Fig. 3, which is the adding position toward which it is drawn by a spring 24, but, if in the movement of the carriage, the roller 21 encounters a subtracting cam on the control bar 23 the bell crank will be swung to shift the reversing pinion 8 to the subtracting position in which the direction of rotation of the shaft 10 is reversed, as stated. It may be noted in passing that an indicator 25 is attached to the shifter 14 to indicate whether the mechanism is set for addition or subtraction.

The squared actuator shaft 10, driven in either direction, as we have seen, carries a laterally movable master wheel or master actuator 26, movable into mesh with successive pinions 27 located in progressive denominational positions and mounted on a shaft 28. The pinions 27 may, for convenience of description, be termed number wheels and they mesh with a corresponding series of registering wheels 29 mounted on a shaft 30, and each having a series of digits from naught to nine which are presented opposite the sight opening 31 in the cross-footer casing 3. As the carriage advances to different denominational positions of the column and presents the primary master wheel 2 to different denominational positions of the register 4, the master wheel 26 of the cross-footer must be moved to corresponding denominational positions so that there will be entire correspondence as to denominational selection of the register 4 and the cross-footer. 100 This denominational selective movement of the master wheel 26 is accomplished by a master wheel carriage 32 mounted to slide laterally on the guide bar 33 and secured to a second bar 34 extended through the walls 110 of the cross-footer casing, (see Fig. 3), and serving as an element of a control mechanism, which is made the subject of a separate application for patent. The carriage 32 engages the grooved hub of the master wheel 26, as shown, so as to move the same laterally without interfering with the rotation of the wheel for addition or subtraction, as specified. The desired movement of the master wheel carriage 32 is effected by what may be termed master wheel advancing mechanism. This mechanism includes a vertically disposed shaft 35, mounted at its lower end in a bearing block 36, carried by a pair of transverse frame bars 37. (See Fig. 11.) The bars 37 also serve to support the block 19, on which the bell crank 20 of the reversing mechanism is fulcrumed. At its upper end the shaft 35 is journaled in a block 38 carried by the bars 12 and 13 and is provided 120 125 130

with an advancing arm 39, engaging a vertical stud 40, projecting from the carriage 32. Intermediate of its ends a fixed collar 41 is secured to the shaft and provided with 5 teeth 42, engaging recesses in the bottom face of the lower arm 43 of the advancing mechanism, this toothed engagement between the arm 43 and the collar 41 being yieldingly maintained by a spring 44 encircling a shaft 10 and interposed between the lever 43 and a set collar 45 on the shaft 35. This connection between the shaft 35 and the arm 43 constitutes a safety device which allows the arm to yield relative to the shaft, if subjected 15 to a strain sufficient otherwise to derange the parts or effect the breakage thereof. At its outer end the arm 43 is provided with a pivoted engaging member 46, the outer end of which is beveled at one side, as indicated 20 at 47, and is adapted to yield vertically. This yielding movement of the engaging member is limited by stops 48 and 49. The pivoted contact piece of the lower arm of the master wheel advancing mechanism is 25 brought into contact with a control device or stop 50, mounted on the control bar 23 and further movement of the carriage, after such engagement, will result in the rotation of the shaft 35, which will swing the arm 39 and cause the carriage 32 to be advanced.

Thus, as the carriage advances step by step across the column, the master wheel of the cross-footer or the cross-footer actuator, as it is variously called, will advance to successive number wheels to rotate the latter upon the depression of the keys. When the arm 43 has finally passed the stop 50 the master wheel 26 will have been advanced beyond the number wheels and its retraction 40 will be effected by a spring 51, projecting from an arm 52, rigid with the arm 39, the opposite end of the spring being secured to a fixed part of the casing, as shown in Fig. 9. When the engaging member 46 of the 45 master wheel advancing mechanism contacts with the control device 50 during the retraction of the carriage, said member will cam up over said device and drop back to normal operative position, after passing the same to 50 permit the master wheel to be again advanced when the carriage again moves forward.

In its movement across the register the master wheel 26 is guided and guarded by 55 a comb plate 53, as is well understood in the art. Also, it is noted in passing, that the intermediate pinions or number wheels 27 are accurately located by detent rollers 54, carried by detent arms 55, urged toward 60 their detaining positions by springs 56. Associated with the number wheels 27 are carrying trips 57, mounted to swing in either direction from a shaft 58 and normally centered by springs 59, which, however, 65 permit the trips to be swung by the wheels

27 in the operation of carrying, whether said wheels are operated for addition or subtraction. Each of the trips 57 is formed with a tooth or projection 60, which normally extends between, but does not interfere with the teeth of adjacent number wheels. Each of these wheels 27, however, is formed, as shown in Fig. 12, with a widened carrying tooth 61, which, as a registering wheel moves from nine to naught, engages a trip 57 and swings the latter to release a carrying dog 62, normally held in its retracted position by a bar 63. A set or series of these carrying dogs 62 are provided, as each number wheel of the series must be carried when the next lower number wheel reaches the limit of its value, with the exception of the wheel of lowest order, which of course is never carried.

A similar set of carrying dogs 62^a, located at the other side of the series of trips 57, are held retracted by a bar 63^a. The two sets of carrying dogs 62 and 62^a are pivotally mounted at their lower ends upon angular levers 64 and 64^a, fulcrumed on fixed shafts 65 and 65^a, which levers constitute what may be termed dog carriers. Each dog is urged toward its normal position, as shown in Fig. 1, by a spring 66 or 66^a, connected at one end to the tail piece of the dog and at its opposite end to the depending arm of the dog carrier, as shown. It will thus be seen that each of the trips 57 controls a pair of dogs mounted on a pair of dog carriers and this opposed relation of the dog carriers makes it possible to employ a single motor spring 67 for each pair of said carriers. These motor springs 67 extend between the depending positions of the carriers and tend to draw the same inward or in a direction to urge the dogs upwardly when released from the bars 63 or 63^a, by the tilting of the intermediate trip as the number wheels are moved in one direction or the other for addition or subtraction.

It will be apparent that when the widened tooth 61 of a wheel 27 engages the upper end of a trip 57 and swings the same, said trip, by engagement with the upper end of a carrying dog, moves the latter from engagement with the bar 63 or 63^a and a motor spring 67 then becomes effective to swing the dog carrier and elevate the dog. This upward movement of the dog causes it to engage a tooth of the wheel 27 of next higher order to the one which operated the trip and to rotate the wheel one additional step, this carrying movement of the dog being limited by one of a pair of stop bars 68 or 68^a, which engages a shoulder 69 on the dog.

Obviously, when the master wheel has traversed the register and has incidentally caused one or more of the carrying dogs to be tripped, it is necessary that these carrying

4

devices be restored in normal position before the adding mechanism will be in condition for a repetition of the adding operation. I, therefore, provide what is known as a restoring frame 70, the two side members 71 of which are fulcrumed on the lower bar 37. At its inner end one of these side members or levers 71 of the restoring frame has an angular arm 72 connected to one end of a 10 retracting spring 73, the opposite end of which is connected to a swinging hook 74, which is connected to a transverse bar 75, adjacent to the lower front side of the register casing, and swung at its lower end from the bar 75 and 15 having a shoulder 76 arranged to bear against the hook 74 is a toggle member 77 pivotally connected at 78 to a second toggle member 79, the lower end of which is swung from a restoring bar 80, connected by a link 20 81 with the bar 35. The second restoring bar 82 is carried by links 83 and 84, the former extending up to the connection 78 between the toggle members 77 and 79 and the other link 84 extending to and pivoted 25 to the bar 35. (See Figs. 13, 14 and 15.)

It will, of course, be understood that this system of toggle members and links is duplicated at opposite sides of the cross-footer so as to support the opposite ends of the restoring bars 80 and 82, each of which extends entirely across one series of dog carriers but located in non-interfering relation therewith. The toggle members 77 are connected with the restoring levers 71 by short 30 links 85. A second retracting spring 86 is connected at one end to the restoring bar 82 and at its opposite end to a fixed part, as indicated at 87.

It will now be seen that if the restoring frame 70 is depressed, the link 85 will spread the toggle formed by the members 77 and 79, thus urging the restoring bar 77 rearwardly to engage and restore any of the carriers 64 which are not in normal 40 position. Similarly, the movement of the links 83 and 84 with the toggle will move the restoring bar 82 toward the front to restore any of the carriers 64 which may have been operated. This restoring operation will be accomplished against the 45 resistance of the springs 73 and 86 which, upon the release of the restoring frame 70, will retract the same to its normal position, at the same time withdrawing the restoring bars 80 and 82 from interfering relation 50 with the dog carriers.

While I have disclosed in another application a means for locking the operating keys of the machine out of action as long as 60 the restoring frame is out of normal position, I prefer to employ as an additional safeguard a full stroke device for the restoring frame, said device comprising a full stroke rack 88 with which coacts a full stroke pawl 89 pivotally mounted on one of the

restoring levers 71 and having an engaging arm 90 and a releasing arm 91, the former coacting with a fixed engaging stop 92 and the latter with one end of the rack 88. A spring urged pivotal detent 93 is disposed 70 to engage a tooth 94, formed on the detent to yieldingly hold the same in either its engaged or disengaged position. The operation of the full stroke device of the restoring mechanism will be clearly apparent from 75 the consideration of Figs. 13, 14 and 15 of the drawings.

In Fig. 13 the restoring frame is in normal position and the detent 93 will engage the rack 88 and prevent retraction of the restoring frame after the upward movement of the latter begins. This action will be obvious from the dotted position of the parts in Fig. 14. When the restoring frame reaches the limit of its downward movement 85 (see the full line showing in Fig. 14), the disengaged arm 90 will engage the stop 92 to withdraw the pawl 89 from cooperative relation with the rack 88, said pawl being retained in its disengaged position by 90 the detent 93 during the retraction of the restoring frame. As the restoring frame reaches the upper limit of its movement, however, the engaging arm 91 of the pawl 95 89 will strike the lower end of the rack 88 and the pawl 89 will be again thrown into cooperative relation with the rack 88, which will be yieldingly held by the detent 93 until again withdrawn in the manner described, upon the complete depression of the 100 full stroke frame.

What I claim is—

1. The combination with a series of number wheels and a master wheel adapted to engage the number wheels in succession, of 105 carrying mechanism including a series of trips operated by the number wheels, two series of carrying members controlled by the single series of trips, and motor springs each of which is common to two carrying members to operate the same when tripped. 110

2. The combination with a series of number wheels and a master actuator, of means for controlling the direction of movement of the master actuator, carrying mechanism 115 cooperating with the number wheels and including a single series of trips, a single series of motor springs, and two series of carrying devices, the carrying devices of both series being operated by the single series of motor springs. 120

3. In a register of the class described, the combination with a master wheel, a series of number wheels and carrying mechanism, of master wheel advancing mechanism including a fixed part, an arm adapted to engage therewith, and a safety release whereby one of said parts will yield. 125

4. In a register of the class described, the combination with a series of number wheels 130

- and carrying mechanism, of a master wheel movable across the series of number wheels, a master wheel carriage, a master wheel advancing mechanism including a shaft having two arms, one engaging the master wheel carriage and a relatively fixed part arranged to be engaged by the other arm, and a yielding safety connection between one of said arms and the shaft.
- 10 5. In a register of the class described, the combination with a series of number wheels and carrying mechanism, of a master wheel movable across the series of number wheels, a master wheel carriage, a master wheel advancing stop and master wheel advancing mechanism including a shaft having two arms, one of which coacts with the stop and the other with the master wheel carriage, means coacting with said shaft to retract the carriage, and a safety release including a toothed connection between one of the arms and the shaft and a spring yieldingly retaining said connection but adapted to permit disconnection of said parts.
- 15 6. In a register of the class described, a master wheel advancing mechanism including a shaft having a collar fixed thereon, an arm mounted to swing on the shaft, a toothed connection between the arm and collar and a spring urging the arm and collar into engaging relation to compel the arm and shaft to move in unison, unless subjected to sufficient stress to release the toothed engagement between the arm and collar against the resistance of the spring.
- 20 7. In a register of the class described, a master wheel advancing mechanism including a shaft and arms extended therefrom, one of said arms having a connection with the shaft which is yieldable under undue stress, and an engaging member carried by said arm to engage a stop, when moved in one direction and having a cam face whereby said engaging member will ride over the stops when moved in the opposite direction, and means for limiting the movement of the engaging device relative to the arm.
- 25 8. In a register of the class described, the combination with a series of number wheels, a series of trips and two series of carrying devices, the opposite carrying devices having tail pieces connected by motor springs, of restoring mechanism including a pair of re-
- storing bars, a system of links having a toggle action for restoring the carrying devices, a restoring frame arranged to operate the toggle, and retracting springs for the restoring frame.
- 30 9. In a register of the class described, the combination with a series of number wheels, a series of trips and two series of carrying devices, the opposite carrying devices having tail pieces connected by motor springs, of restoring mechanism including a pair of restoring bars, and a system of links having a toggle action, for restoring the carrying devices, a restoring frame arranged to operate the toggle, retracting springs for the restoring frame, and a full stroke device for the restoring frame, and a full stroke device for the restoring frame.
- 35 10. In a register of the class described, the combination with a series of number wheels, a series of trips and two series of carrying devices, the opposite carrying devices having tail pieces connected by motor springs, of restoring mechanism including a pair of restoring bars, a system of links having a toggle action for restoring the carrying devices, a restoring frame arranged to operate the toggle, retracting springs for the restoring frame and a full stroke device for the restoring frame, said full stroke device including a fixed rack and a full stroke pawl carried by the restoring frame and having engaging and releasing arms, means coacting with said arms at the opposite limits of movement of the frame, and a detent yieldingly retaining the pawl in its engaged and disengaged positions.
- 40 11. In a register of the class described, a series of denominational members movable in different directions for addition and subtraction, two sets of carrying devices coacting with the denominational members, a single series of trips controlling the two series of carrying devices, and motor springs each of which is common to a plurality of carrying devices to operate the same when tripped.

In testimony whereof I hereunto affix my signature in the presence of two witnesses.

HARRY ARTHUR FOOTHORAP.
